Attorney

UNITED STATES PATENT OFFICE.

JOSEPH S. BOHATKA, OF CHICAGO, ILLINOIS.

WINDOW.

Application filed September 28, 1925. Serial No. 59,028.

My invention relates to improvements in swinging windows, and has more particularly for its object to provide certain novel features in the construction, form, and arrangement of the several parts whereby the upper and lower sashes may not only be raised and lowered, but may also be swung into different inclined positions with respect to the window-frame.

With the above and other objects in view my invention consists in the novel combination, construction and arrangement of the parts and members shown in one embodiment in the accompanying drawings, described in the following specifications, and particularly pointed out in the appended claim.

In the illustrations, Fig. 1, is a vertical section through a window embodying my invention;

Fig. 2, is the same section but showing the sash in inclined position;

Fig. 3, is a cross section taken on line 3-3 of Fig. 1;

Fig. 4, shows an enlarged detail of the guide bolt and cable support which is securely mounted to the bottom of the lower rails of the sash;

Fig. 5, shows the latch bolt engaging the guide bolt for retaining the lower end of the sash when the sash are held in inclined position as shown in Fig. 2;

Fig. 6, is an elevation of the latch bolt;

Fig. 7, is a cross section of the parting strip and sash stop retaining bolt taken on line 7-7 of Fig. 1;

Fig. 8, is a front elevation of the keepers for the parting strip and sash stop retaining bolts;

Fig. 9, is an elevation of the upper corner of the sash showing the cup bearing embedded therein; and,

Fig. 10, is a cross section of the cup bearing taken on line 10-10 of Fig. 9.

Referring now in detail to the illustrations, the upper sash is indicated by numeral 20 and the lower sash by numeral 21.

The sash are mounted for vertical sliding movement between the blind stop 22 and sash stop 23 and a parting strip 24 extends between the paths of the sash.

The pulley stile 25 is provided with longitudinal grooves 25^A into which extend the heads of the guide bolts 26 which are se-

curely mounted to the bottoms of the lower 55 sash rails. It will be observed that the sash do not touch the pulley stile but are spaced therefrom to permit the passage of the counterweight cable 27 therebetween for connection to the guide bolts 26.

While the sash are partially guided by the engagement of the guide bolts 26 within the grooves 25^A of the stile 25, the sash are also guided during the vertical movement or stationary vertical position between the parting strip 24 and the sash stop 23.

The invention here presented includes the hinging of the parting strips 24 and the sash stop 23 near their upper ends so that the greater portions of same may be swung 70 outwardly about their respective hinges 24^A and 23^A as shown in Fig. 2. But in order to permit this swinging movement the strip 24 and stop 23 are also broken near their lower ends and provided with hinges respectively 24^B and 23^B, as otherwise same would not pass the stool board 28.

The strip 24 and stop 23 when in normal vertical position are securely held to the pulley stile 25 by retaining bolts 29 which 80 extend through the body of the strip and stop and are provided with a head 29^A and shoulder 29^B. The passage 29^C is slightly enlarged near the outer face for a coil spring 30 which tends to push the bolt 29 85 out of the keeper 31 which is imbedded in the face of the pulley stile 25. The keeper 31 has a slotted entrance opening 31^A through which the narrow flat inner head 29^B extends so that when the bolt 29 is 90 turned with the head 29^B at right angles to the longitudinal axis of the opening 31^A the bolt is securely held in the keeper by the action of the spring 30 tending to push it out.

In order to afford cleaning of the window 95 sash the upper sash is lower so that the guide bolts 26 come below the latch bolts 32 which pass over same to retain it against upward movement by the sash counterweights. The bolts 32 are slidably mounted 100 in the housings 33 which are mounted on the stile 25. With the bolts 32 retaining the sash against upward movement, the upper end of the sash may be supported on the heads of the retaining bolts 29 near the lower 105 ends of the parting strip 24, the lower sash is held in inclined position in like manner.

Both upper and lower sash are provided

with cup-like bearings 34 which are imbedded in the upper rails thereof for receiving the heads of the retaining bolts 29.

I claim:

- 5 A window comprising a pair of sash, a frame having a pulley stile between which said sash are slidably mounted, a pair of parallel grooves in said stile extending vertically thereof and in alignment with the
- 10 longitudinal center line of the side rails of said sash, a guide bolt for each sash fixed to the lower end of said sash and extending into said groove, a counter weight cable fixed to each of said bolts, a fixed blind stop to
- 15 guide one side of the upper sash, a parting strip between said sash, a sash stop to guide the lower sash on the inner side thereof, both of said sash being spaced from said pulley

stile to provide clearance for said counter weight cables, said parting strip and sash stop being divided and provided with a hinge at said divisions to permit their outward movement into angular positions to thus afford the tilting of both of said sash about said guide bolts into substantially lateral position, means for retaining the lower ends of said sash against the pull of said counterweight cables, means for supporting the upper end of said upper sash on said parting strip during tilted position, and means for supporting the upper end of said lower sash on said sash stop during tilted position.

In witness whereof I affix my signature.

JOSEPH S. BOHATKA.
